UNITED STATES PATENT OFFICE.

WILLIAM DEMUTH, OF NEW YORK, N. Y.

DESIGN FOR PIPE-STEM.

Specification forming part of Design No. 7,906, dated December 1, 1874; application filed November 13, 1874.
[Term of Patent 3½ years.]

To all whom it may concern:

Be it known that I, WILLIAM DEMUTH, of the city, county, and State of New York, have invented a Design for Pipe-Stem, of which the following is a specification:

The nature of my design is fully represented in the accompanying drawing.

The invention consists in the design of a tree twig or branch, tapering from one end to the other, having a stump near its one end, and curved in opposite directions, whereby a rustic appearance is imparted to the article, by which it can readily be distinguished from others of its class.

In the drawing, the letter A designates my stem, which tapers from one end to the other, and the surface of which is roughened in imitation of a tree twig or branch. Near the thick end of the stem is a stump, B, which has a level top, and near the thin end of the stem is a smooth space, C. The stem is curved in opposite directions, as shown in the drawing.

What I claim as new, and desire to secure by Letters Patent, is—

The design for a pipe-stem or cigar-holder, substantially as shown and described.

In testimony that I claim the foregoing I have hereunto set my hand this 5th day of November, 1874.

WM. DEMUTH.
